UNITED STATES PATENT OFFICE.

GEORGE C. YOCUM, OF SCRANTON, PENNSYLVANIA.

COIN-ASSORTING MECHANISM.

No. 866,763.

Specification of Letters Patent.

Patented Sept. 24, 1907.

Application filed August 30, 1906. Serial No. 332,598.

To all whom it may concern:

Be it known that I, GEORGE C. YOCUM, a citizen of the United States, residing at Scranton, in the county of Lackawanna and State of Pennsylvania, have invented certain new and useful Improvements in Coin-
Assorting Mechanism, of which the following is a specification.

This invention relates to improvements in coin assorting chutes, particularly adapted for use in coin operated vending machines such as that illustrated in my copending application Serial No. 332,699 and in my Patent No. 841,210.

In the accompanying drawing, which illustrates my invention, Figure 1 is a side elevation of the coin assorting chutes arranged upon one end of the casing of a vending machine, the casing being shown in vertical section; Fig. 2 is a front elevation, and Fig. 3 a top plan view of the chutes, showing also a portion of the end of the casing which supports the chutes.

20 The vending machines shown in the applications above referred to are arranged to cut off and deliver a ticket, having a purchasing value of five cents, each time a five cent piece or "nickel" enters a certain compartment in the coin balance of the machine, and to 25 cut off and deliver two such tickets when a dime enters another compartment in the coin balance.

The principal purpose of the present invention is to provide means for delivering the dimes and nickels, inserted in a common coin slot, into the appropriate compartments of the coin balance of such machine and also to prevent coins of other denominations from entering such compartments, and to prevent one coin from entering any compartment of the coin balance while the machine is being operated by another coin.

30 As the chutes are arranged to sort the coins according to their diameters, it will be obvious that by differently proportioning the parts they may be made suitable for assorting coins of other sizes than nickels, dimes and pennies; but in the drawings I have shown them suitable for delivering dimes and nickels, one at a time, into the vending machine and for ejecting pennies.

Referring to the drawings, A indicates a portion of the casing or support and B indicates the system of coin chutes. A single coin slot 1 is provided in the upper part of the casing and forms the upper end of the system of chutes. As the chutes shown in the drawings are proportioned for dimes, nickels and one cent pieces, the coin slot is made just large enough to receive a five cent piece and to prevent the insertion of a larger coin. The chutes X-V, X and V, are all open at one side, as shown, and provided with coin retaining flanges extending along the tops and bottoms of the chutes on the sides which are away from the supporting end 2 of the casing. These chutes are supported on the 55 end of the casing by posts 3, and are inclined, or lean

away from said end at the top so that coins passing down through the chutes will lean against the top flanges of the chutes. The chute X-V has a vertical part 1^a leading down from the coin slot, and the body of the chute inclines away from said vertical part. The chute X-V has at its open side the lower flange 3^a, and it also has an upper flange 4, the lower edge of which is at such distance above the bottom of the chute that a coin of the diameter of a dime will not be engaged by the flange 4, while a coin of larger diameter, such as a penny or a nickel will be engaged by said flange 4 and retained within the chute.

Upon the interior of the wall of the chute X-V and at the upper part thereof is arranged a cam or projection 5 which deflects the upper part of a dime passing down the chute X-V and throws it out of said chute into a hopper or receiver 6 having flaring sides and forming the upper end of the chute X which latter inclines in the opposite direction from the chute X-V, and then extends vertically downward as shown. This receiver 6 is suitably formed to keep the dime upon its edge and direct it into the main part of the chute X, which has flanges 7 and 8 for retaining the dime in the chute until it passes from the lower end of the chute. The chute V, which is a continuation of the chute X-V, connected to it by a curved portion b, and inclining in the opposite direction has flanges 9 and 10 which will retain a five cent piece. A five cent piece inserted in the coin slot will, therefore, be carried to the lower end of the chute V. The first or upper portion 9^a of the flange 9 is low enough to retain a coin of the diameter of a penny, but the remainder of this flange is cut away as indicated at 9^b so that the distance between the bottom of the chute and the lower edge of the portion 9^a is greater than the diameter of a penny. If a penny is inserted in the machine it will go down through the chute X-V and into the chute V and it will then be ejected by a cam or projection 11, secured to the inner side of the chute V. The penny after leaving the chute V will fall into a hopper 12 leading to a return trough or chute 12^a and be conducted out through an opening 13 in the casing and thus returned to the person who inserted the penny in the slot.

The lower ends x and v of the coin chutes X and V are both bent out of line with the main portions of the chutes and directed toward the return chute 12^a so as to deliver coins into the return chute when nothing interferes to deflect the coins in their flight.

Beneath the lower ends of the chutes X and V which are in line with one another is arranged a narrow stationary casing or receptacle 14, within which the coin balance of the vending machine is located. This receptacle has extending along one of its upper edges, and forming a continuation of the side of the receptacle

which is next to the chute 12^a, a hinged deflecting plate 14^a, which is movable by means of a rod 15 into position to deflect coins passing from the lower ends of the coin chutes, and direct them into said receptacle.

5 The deflecting plate is shown in this position in full lines in Fig. 2. A movement of the rod to the left in said figure draws the plate into the position shown in dotted lines, and allows coins to pass from the coin chutes X and V to the chute 12^a. A dime or nickel, 10 therefore, passing through the chutes X or V will pass into the chute 12^a or the receptacle 14, according to the position of the hinged plate 14^a.

The plate 14^a in the machine shown in my application, Serial Number 332,699¹ is normally held in the 15 position shown in full lines in Fig. 2, when the machine is stopped, in which position a dime or nickel dropped into the machine at the coin slot 1 will pass into the receptacle 14, (which contains the coin balance) and a motor, started into operation by the movement 20 of the balance, moves the rod 15, which in turn moves the plate 14^a, to the position shown in dotted lines, in which position it remains while the motor is in operation. When the motor stops the plate 14^a is automatically returned to normal position. It will be seen, 25 therefore, that if a dime or nickel enters the machine while the motor is stopped it will enter the receptacle 14; but if a second dime or nickel is inserted in the machine while the motor is in operation it will pass to the return chute 12^a and be carried out of the casing 30 of the machine through the opening 13. Pennies inserted into the coin slot will always pass into the return chute, and coins of larger size than nickels cannot pass through the coin slot. By differently proportioning the coin slot and chutes, however, coins of various 35 other denominations may be assorted, as will be evident.

Having thus described my invention what I claim is—

1. In a coin assorting mechanism, an upper assorting chute having guiding means for coins of larger diameter than dimes and ejecting means for dimes, a lower assorting chute forming an extension of said upper chute and having means for ejecting pennies and guiding means for coins of larger diameter than pennies, a conducting chute for receiving the dimes ejected from said upper chute, a return 40 chute arranged below the lower ends of said lower assorting chute and said dime conducting chute, and a device adapted to be moved into position to deflect the coins passing from said latter chutes and prevent their entrance into the return chute.

2. In a coin assorting mechanism, an upper assorting chute having guiding means for coins of larger diameter than dimes and ejecting means for dimes, a lower assorting chute forming an extension of said upper chute and having means for ejecting pennies and guiding means for coins of larger diameter than pennies, a conducting chute 50 for receiving the dimes ejected from said upper chute, a return chute arranged to receive the ejected pennies and also to receive the coins from the ends of the lower assorting chute and dime conducting chute, and a device adapted to be moved into position to deflect the coins passing from the latter chutes and prevent their entrance into the return chute.

3. In a coin assorting mechanism, a return chute, an upper assorting chute having guiding means for five cent pieces and pennies and ejecting means for dimes, a conducting chute having its upper end arranged to receive the ejected dimes and its lower end arranged to deliver the dimes to the return chute, a lower assorting chute arranged to conduct five cent pieces from the upper chute to the return chute and having means for ejecting pennies, 65 and movable means for deflecting coins passing from said dime conducting chute and lower assorting chute and preventing the coins from passing into the return chute.

4. In a coin assorting mechanism, a return chute, an upper assorting chute having guiding means for five cent pieces and pennies and ejecting means for dimes, a conducting chute having its upper end arranged to receive the ejected dimes and its lower end arranged to deliver the dimes to the return chute, a lower assorting chute arranged to conduct five cent pieces from the upper chute to 70 the return chute and having means for ejecting pennies, a hopper at the upper end of the return chute for receiving the ejected pennies, and movable means for deflecting coins passing from said dime conducting chute and lower assorting chute and preventing the coins from passing into the 75 return chute.

5. In a coin assorting mechanism a return chute, an upper assorting chute, open at one side to permit dimes to be ejected laterally therefrom and having flanges adapted to retain five cent pieces and pennies, said chute having 80 therein a fixed cam or projection for ejecting the dimes, a chute having its upper end arranged to receive the ejected dimes and its lower end arranged to deliver the dimes to the return chute, a lower assorting chute, inclined oppositely to said upper assorting chute, and having one side 85 open to permit pennies to be ejected therefrom, and having flanges arranged to conduct five cent pieces to the assorting chute, and having also a cam therein for ejecting pennies, and a deflecting device movable to prevent the five cent pieces and dimes from passing into the return chute. 90

In testimony whereof I affix my signature, in presence of two witnesses.
